[57] CLAIM

The ornamental design for a "coat and purse hanger," as shown and described.

DESCRIPTION

FIG. 1 is a front elevational view of a "coat and purse hanger" showing my new design;

FIG. 2 is a top plan view thereof;

FIG. 3 is a bottom plan view thereof;

FIG. 4 is a rear elevational view thereof; and,

FIG. 5 is a right side elevational view thereof, the left side elevation being the same.
